CLAIM

The ornamental design for a dental air/water syringe tip, as shown and described.

DESCRIPTION

FIG. 1 is a front, right perspective view of a dental air/water syringe tip showing a first embodiment;

FIG. 2 is a rear, right perspective view thereof;

FIG. 3 is another rear, right perspective view thereof;

FIG. 4 is a right-side elevation view thereof;

FIG. 5 is a left-side elevation view thereof;

FIG. 6 is a front elevation view thereof;

FIG. 7 is a rear elevation view thereof;

FIG. 8 is a top plan view thereof;

FIG. 9 is a bottom plan view thereof;

FIG. 10 is a front, right perspective view of a dental air/water syringe tip showing a second embodiment;

FIG. 11 is a rear, right perspective view thereof;

FIG. 12 is another rear, right perspective view thereof;

FIG. 13 is a right-side elevation view thereof;

FIG. 14 is a left-side elevation view thereof;

FIG. 15 is a front elevation view thereof;

FIG. 16 is a rear elevation view thereof;

FIG. 17 is a top plan view thereof; and,

FIG. 18 is a bottom plan view thereof.

All features in phantom line are for the purpose of illustrating environmental structure and form no part of the claimed subject matter.

1 Claim, 12 Drawing Sheets
